END BELL CONSTRUCTION

Andrew V. D. Willgoos, deceased, late of West Hartford, Conn., by Hartford National Bank and Trust Company, executor, Hartford, Conn., assignor to United Aircraft Corporation, East Hartford, Conn., a corporation of Delaware

Application August 3, 1950, Serial No. 177,452

3 Claims. (Cl. 230—122)

1

The present invention relates to a rotor construction and particularly to the end bell for an axial flow compressor rotor.

In order to withstand the thermal stresses set up in the end bell as well as the stresses set up by the differential expansion between the end bell and the adjacent rotor disc, it has previously been customary to make the end bell extremely heavy providing a rigid structure by which to engage and clamp the end disc of the rotor against the remaining discs. A feature of this invention is an arrangement of the end bell such that the weight may be materially reduced without affecting the ability of the end bell to carry the load imposed thereon.

Another feature of the invention is an arrangement of the end bell with a substantially cylindrical flange concentric to and substantially the same diameter as the flange on the rotor disc engaged thereby such that the cylindrical flange may be relatively thin and thereby capable of expansion or contraction with the adjacent disc.

Other objects and advantages will be apparent from the specification and claims, and from the accompanying drawings which illustrate an embodiment of the invention.

Fig. 1 is a sectional view longitudinally through a compressor showing the end bell construction.

Fig. 2 is an enlarged sectional view of the end bell.

Fig. 3 is a fragmentary sectional view along the line 3—3 of Fig. 2.

The invention is shown in a multistage axial flow compressor having a casing 2 supporting a number of rows 4 of stationary vanes extending radially inward from the casing. The vanes alternate with rows of blades 6 mounted on the periphery of the compressor rotor 8. In the arrangement shown the rotor is built up of a number of separate discs 10 each carrying one row of the blades 6 with the discs arranged in stacked concentric relation and held together by a centrally located through bolt 12 extending between the end bells 14 and 16 located at opposite ends of the rotor. Each disc 10 has laterally extending flanges 18 concentric to and spaced from the axis of the disc and engaging at their end surfaces with the cooperating flange on the adjacent disc to provide the proper axial spacing of the discs and to form in effect a blade sup-

2

porting cylinder by the axial alignment of all of the flanges 18. The adjacent flanges may have radially extending face splines 20 thereon to aid in piloting the discs and to transmit torque between adjacent discs.

The endmost disc has a projecting flange 22 on the outer side of each disc for engagement with the end bell and each end bell has a cylindrical flange 24 or 26 in alignment with the flanges 18 and of a relatively thin construction to allow the end of the cylindrical flange engaging with the flange 22 to expand and contract radially with the thermal expansion of the disc.

Each end bell has a sleeve portion or hub 28 through which the bolt 12 extends and the outer surface of the sleeve may have a cylindrical bearing portion 30 to receive the inner race of a bearing 32 which supports the end of the rotor concentrically within the casing. The end of the cylindrical sleeve portion 28 of the end bell adjacent to the rotor discs has a heavy radially extending flange 34 with the outer periphery of which the cylindrical flange 24 is made integral. The radial flange especially the surface facing the adjacent disc preferably slopes away from the disc, as shown. With an arrangement of this character the radial flange of the end bell which is approximately the same diameter as the annular flange on the disc is made heavy enough to withstand the axial loads developing thereon during the operation of the compressor but the cylindrical flange forming the connection between the radial flange on the end bell and the adjacent disc is such that expansion of the disc is not impeded by the end bell and the intermeshing face splines are not caused to slide radially relative to one another thereby possibly causing galling. The cylindrical flange extends at a substantial angle, approximately a right angle, to the radial flange, as will be apparent, and the intersection between the flanges is abrupt as shown. The radial flange is preferably tapered toward its outer edge to be substantially a constant stress type of flange, and the cylindrical flange carrying primarily compressive stresses may thus be thinner than if it were loaded in bending.

The hub portion 28 of the end bell is substantially smaller in external diameter than the cylindrical flange 24, and the end of the hub

portion projects within the cylindrical flange. The radial flange 34 projects outwardly from the end of the hub portion adjacent to the compressor disc and has its opposite side surfaces converging in a radially outward direction such that the flange is relatively thick at the hub and tapers to a substantially thinner dimension adjacent its outer edge. The side surface of the radial flange remote from the adjacent disc extends in a substantially radial direction and the opposite side surface, as above stated, slopes away from the adjacent disc in a radially outward direction. At the junction of the radial and cylindrical flanges a relatively heavy ring 35 is formed for the purpose of more uniformly distributing the stresses from the cylindrical flange 24 into the radial flange 34.

To assist in piloting the discs with respect to one another and with respect to the end bells, the rotor may have in radial alignment with each intermeshing row of face splines a sleeve or ring 36 which, as best shown in Fig. 2, has its outer corners notched as at 38 to engage with cooperating shoulders 40 on the flanges 18 and 24 to support the sleeve in such a manner that it cannot move axially within the rotor. It will be apparent that assembly of the rotor in an arrangement of this type is relatively simple since the discs may be arranged in stacked relation one on another, being piloted by the face splines and by the rings 36 until the rotor and the end bells are all assembled.

The through bolt may then be placed in position and clamped up tight by a suitable nut (not shown) thereby clamping the entire rotor elements into a rigid assembly. The through bolt may be arranged as described in Soderberg Patent No. 2,461,242. With the flanges 18 located at a substantial distance from the axis of the rotor it is apparent that a substantial rigidity is imparted to the rotor thereby to minimize bending during the operation of the device.

It is to be understood that the invention is not limited to the specific embodiment herein illustrated and described, but may be used in other ways without departure from its spirit as defined by the following claims.

What is claimed is:

1. In a rotor construction, at least one disc having a row of blades on its periphery and having a central opening, an end bell at each side of the disc and a through bolt extending between the end bells for holding the disc and end bells in assembled relation, said disc having an annular flange on one side surface thereof concentric to and spaced from the axis of the disc and also spaced from the opening in the disc, one of said end bells having a cylindrical flange thereon corresponding in diameter to the flange on the disc for endwise engagement between the flanges when the rotor is assembled, said end bell also including a central hub portion substantially smaller in diameter than the cylindrical flange and concentric thereto, and a radially extending flange integral with said hub portion and said cylindrical flange, said radial flange having its opposite side surfaces converging in a radial direction outwardly from the axis of the end bell such that the flange is relatively thick at its connection to the hub portion and tapers to a substantially thinner axial dimension adjacent its outer edge, the side surface of the radial flange remote from the adjacent disc being substantially radial, and the opposite side surface of the radial flange sloping away from the adjacent disc in

a radial direction outwardly from the axis of the end bell, the cylindrical flange extending at an abrupt angle to the radial flange at its periphery.

5. In a rotor construction, at least one disc having a row of blades on its periphery and having a central opening, an end bell at each side of the disc and a through bolt extending between the end bells for holding the disc and end bells in assembled relation, said disc having an annular flange on one side surface thereof concentric to and spaced from the axis of the disc and also spaced from the opening in the disc, one of said end bells having a cylindrical flange thereon corresponding in diameter to the flange on the disc for endwise engagement between the flanges when the rotor is assembled, said end bell also including a central hub portion substantially smaller in diameter than the cylindrical flange and concentric thereto, and a radially extending flange integral with said hub portion and said cylindrical flange, said radial flange having its opposite side surfaces converging in a radial direction outwardly from the axis of the end bell such that the flange is relatively thick at its connection to the hub portion and tapers to a substantially thinner axial dimension adjacent its outer edge, the side surface of the radial flange remote from the adjacent disc being substantially radial, and the opposite side surface of the radial flange sloping away from the adjacent disc in a radial direction outwardly from the axis of the end bell, the cylindrical flange extending at an abrupt angle to the radial flange at its periphery.

10. In a rotor construction, at least one disc having a row of blades on its periphery and having a central opening, an end bell at each side of the disc and a through bolt extending between the end bells for holding the disc and end bells in assembled relation, said disc having an annular flange on one side surface thereof concentric to and spaced from the axis of the disc and also spaced from the opening in the disc, one of said end bells having a cylindrical flange thereon corresponding in diameter to the flange on the disc for endwise engagement between the flanges when the rotor is assembled, said end bell also including a central hub portion substantially smaller in diameter than the cylindrical flange and concentric thereto, the end of the hub portion adjacent to the disc being radially surrounded by the cylindrical flange and a radially extending flange integral with said hub portion and said cylindrical flange, said radial flange projecting radially from the end of the hub adjacent to the disc, and said radial flange having its opposite side surfaces converging in a direction away from the axis of the end bell such that the flange is relatively thick at its connection to the hub and tapers to a substantially thinner axial dimension adjacent its outer edge, the side surface of the radial flange remote from the adjacent disc being substantially radial and the opposite side surface sloping away from the adjacent disc in a radial direction outwardly from the axis of the end bell, the cylindrical flange extending at an abrupt angle to the radial flange, the end of the hub adjacent to the disc and the end of the cylindrical flange which engages with

5

the annular flange on the disc lying substantially in the same radial plane.
